UNITED STATES PATENT OFFICE.

WILLIAM ROGERS, OF HARTFORD, CONNECTICUT.

DESIGN FOR SPOON AND FORK HANDLES.

SPECIFICATION forming part of Design No. 11,657, dated February 24, 1880.

Application filed January 13, 1880. Term of patent 34 years.

To all whom it may concern:

Be it known that I, WILLIAM ROGERS, a citizen of the United States, residing at Hartford, in the county of Hartford and State of Connecticut, have invented and produced a new and original Design for the Handles of Spoons, Forks, &c., of which the following is a specification, reference being had to the accompanying drawing, forming a part thereof, in which is represented a front view of a spoon having my newly-designed handle.

The invention relates to a design for the handles of spoons, forks, and like articles of table-service; and it consists in the peculiar configuration of the tip of the handle, in connection with a bold ornament and fillet designed for adaptation to said configuration, as will be hereinafter more fully described.

Starting from the body or bowl, the handle is provided nearly half-way of its length (or thereabout, according to the article) with a boss, *a*, and from there gradually expands in two curved lines, *b b*, terminating in two segments, *c c*, of a circle united by a half-circle, *d*, of much smaller radius. The upper end of the handle is provided with a fillet starting from the lowest point on the boss *a*. It follows without break the curved lines *b*, segments *c*, and the edge of the half-circle *d*.

From the upper end of the surface inclosed by said fillet depends a bold ornament, *e*, of the honeysuckle pattern, the tendrils of which are united by a band, *e'*, and then extended above said band to form a small crown, *d'*, surrounded by the fillet of the half-circle *d*, forming the tip of the handle.

Heretofore spoon-handles have been ornamented with designs of a honeysuckle pattern, and the end provided with a continuous segmental fillet; but I am not aware that said honeysuckle designs have had their upper end so formed as to represent a crown; neither am I aware that such a crown has been placed within the tip of the spoon-handle in a continuous fillet on said tip and extending therefrom over the boss *a* of the handle.

I claim—

The herein-described design, consisting of ornamentation of the honeysuckle pattern *e*, having its upper end formed to represent a crown, *d'*, and having the latter inclosed within a semicircular tip, *d*, provided with a fillet following the contour of the handle, as shown in the accompanying drawing.

WILLIAM ROGERS.
